UNITED STATES PATENT OFFICE.

CHARLES F. WILLIAMS AND IRA C. WILLIAMS, OF COLDWATER, MICHIGAN.

FLUID-HYDROCARBON BURNER.

1,072,548.

Specification of Letters Patent. Patented Sept. 9, 1913.

Application filed October 17, 1912. Serial No. 726,334.

To all whom it may concern:

Be it known that we, CHARLES F. WILLIAMS and IRA C. WILLIAMS, citizens of the United States, residing at Coldwater, in the county of Branch, State of Michigan, have invented a new and useful Fluid-Hydrocarbon Burner, of which the following is a specification.

The present invention relates to improvements in fluid hydrocarbon burners.

The primary object of this invention is the provision of a novel form of burner, in which the fluid hydrocarbon is supplied to a directing valved nozzle through a plurality of tubes or pipes which constitute the gasifying chamber, the same being disposed to be heated by the flame from the burner or jet tube, there being mounted upon such burner or jet tube, a reflecting means whereby the flame from the jet is directed to the desired location upon the top of the stove or carrying casing of the burner, so that the heat may be centralized upon the object desired to be heated.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a longitudinal sectional view through the casing carrying the burner with the reflector shown partly in section, there being means shown diagrammatically for supplying the fluid hydrocarbon under pressure to the burner. Fig. 2 is an end elevation taken from the nozzle side of the burner. Fig. 3 is a section taken on the line 3—3 of Fig. 1. Fig. 4 is a diagrammatic plan view of the oil conducting conduit, the same being broken away to reduce the longitudinal length of the view.

Referring to the drawings, the numeral 1 designates the oil or fluid hydrocarbon supplying tank which has air supplied thereto through the pump 2, there being a conduit 2' led away from the tank near the lower end thereof to supply the oil to the inlet tube 3 of the gasifying pipes 4, 5 and 6, there preferably being three of these pipes disposed in parallel relation and in

communication with each other. These pipes as clearly shown are mounted in the upper portion of the casing 13 which may constitute a utensil support for the utensils to be heated or will constitute a casing to be disposed within the fire box of any form of stove or furnace.

A vertically disposed tube or pipe 7 is led from the gasifying pipe 6 and has connected thereto, the casing 8 controlled by the needle valve 9 so that the gas or heated oil may be supplied through the nozzle 10 across the space between the open mouth of the burner tube 11 into such burner tube. This burner tube 11 as clearly shown in Fig. 1 is disposed longitudinally of the casing 13 and is mounted in the respective end walls thereof, being held in place by means of the brackets or sockets 12. The outer end of the tube 11 is sealed as at a so that the gas is directed through the perforations of the tube. By this means it will be seen that the introduction of the gas or heated oil into the open end of the burner tube 11 will draw there within the necessary amount of air from the surrounding atmosphere so as to produce a blue flame through the jet tube or apertures of the burner 11 and within the casing 13. The burner 11 as clearly shown is disposed below and in heating relation to the gasifying pipes 4, 5 and 6, and as herein shown directly below, although it is apparent that the same may be to one side but still be within the casing 13, the arrangement being varied according to the intensity of the heat upon the pipes 4, 5 and 6.

In order to provide a means for directing the flames from the burner tube 11, to various portions of the open portion of the casing 13, a plurality of brackets 14 are rotatably mounted upon the tube 11 beyond the perforated portion thereof and these brackets 14 each are secured to and carry the longitudinally disposed and concaved reflector or plate 15, which normally will assume the position as shown in Fig. 3, the fit between the brackets 14 and the tube 11, however, being comparatively tight, so that the member 15 may be moved to any angular position with the tube 11 as its axis and be retained in such position by the friction of the brackets upon the tube.

In order to properly manipulate the concaved plate 15 to assume any of the necessary positions, with relation to the burner

tube 11, a handle or pin 16 is connected to one end of the curved plate or reflector 15 and is projected through the arc-shaped slot 17 formed in the end wall of the casing 13 and in ready access to the operator.

In order to provide a priming means to heat the casing 8, at the initial starting of the burner, a drip cup 18 is carried by the casing 8 and in this is poured the necessary 10 priming fluid, such as gasoline, or alcohol, to be ignited and thus heat the casing 8 before the introduction of the oil from the gasifying pipes 4, 5 and 6 into the casing and the initial introduction of the gas into 15 the open end of the burner tube 11. After such introduction, the gas is ignited from the jets of the tube 11, and the flame is directed to heat the gasifying pipes 4, 5 and 6, so that the oil contained therein will 20 be heated to the necessary temperature to gasify and being under pressure due to the air supplied to the tank 1, a continuous supply of gas will be the result in the tube 11 and as the nozzle 10 is in spaced relation to 25 the inlet end of the burner tube 11, the necessary air is injected into tube 11 for supplying the desired amount of oxygen to the gas. It is also evident that by reason of the reflector or curved plate 15, that the heat from the 30 flames may be directed or concentrated where desired for producing the necessary result in any form of stove, or upon utensils when the casing 13 constitutes a stove casing for cooking and other purposes.

35 What is claimed is:

1. In a fluid hydrocarbon burner, a supporting casing, a gasifying coil disposed therein, a burner tube disposed in said casing below the gasifying coil, a longitudinally disposed reflector plate mounted within the casing upon the burner tube for swinging movement, and manually controlled means connected to the reflector plate and operable exteriorly of the casing 40 for rotating the plate relatively to the burner tube.

45 2. In a fluid hydrocarbon burning apparatus, a supporting casing, a plurality of gasifying conduits located therein, a gas di-

recting nozzle in communication with the 50 conduits, a burner tube mounted in the casing below the conduits and having its inlet end adjacent to the nozzle, a plurality of brackets rotatably mounted upon the burner tube within the casing, a reflector plate carried by said brackets, and manually operated means connected to the plate and disposed exteriorly of the casing for 55 for rotating the plate relatively to the tube.

3. In a fluid hydrocarbon burning apparatus, a supporting casing, a plurality of gasifying conduits located therein, a valve casing having a gas directing nozzle connected to receive the gas from the gasifying 60 conduits, a longitudinally disposed burner tube mounted in the casing and having an open inlet end disposed exteriorly of the casing with the nozzle concentrically thereof and in spaced relation thereto, a pair of 65 brackets rotatably mounted upon the tube, a curved reflector plate carried by said brackets, and means connected to the plate and operable exteriorly of the casing for 70 rotating the plate relatively to the burner 75 tube.

4. In a fluid hydrocarbon burning apparatus, a plurality of gasifying conduits, a valve controlled gas supplying nozzle connected thereto, a longitudinally disposed 80 burner tube disposed to receive the gas from the nozzle and in heating relation to the gasifying conduits, a plurality of brackets rotatably mounted upon the burner tube within the casing, a curved plate carried by 85 said brackets and in reflecting relation to the burner tube, and a handle for operating said plate connected to the plate and projecting exteriorly of the casing.

In testimony that we claim the foregoing 90 as our own, we have hereto affixed our signatures in the presence of two witnesses.

CHARLES F. WILLIAMS.
IRA C. WILLIAMS.
